DEVICE FOR SUPPORTING PACKAGED ARTICLES AND THE LIKE

Asger Eilersgaard, Los Angeles, Calif., assignor to
The Patent and Licensing Corporation, New
York, N. Y., a corporation of Massachusetts

Application November 5, 1942, Serial No. 464,600

7 Claims. (Cl. 206—47)

This invention relates generally to receptacles or containers and is concerned with the provision of a supporting device adapted especially for confining and retaining packaged articles and the like within a hollow cylindrical roll of sheet material.

The device of my invention is adapted particularly for use in shipment of asphaltic roofing material furnished in long relatively narrow sheets. This material is usually wound for shipment in the form of rolls, the rolls having an axial opening which may be of a diameter ranging from approximately 3 to 6".

It has been common practice for many years to enclose within this axial opening the "trimmings" required for each roll of material, these "trimmings" usually comprising a container, such as a can, of lap cement for adhesively joining overlapping roofing sheets together, and a carton or package of nails suitable for securing the laid sheets to the underlying roof support. In order to retain the "trimmings" within the follow opening of the roll until removal thereof is required on the particular job for which the rolled material is intended, it has been customary to seal the open ends of the roll by means of suitable heads or caps, usually muslin cloth reinforced with cardboard and pasted to the ends of the roll. This method of loosely confining the packaged articles within the hollow rolls not only consumes a substantial amount of material and labor, but not infrequently the handling of the roll results in damage or displacement of the heads or caps, with consequent loss of or damage to the packages. This occurs not only in handling of the rolls in transit, but also in storage, particularly during the time the adhesive securing the caps or heads to the rolls is still wet so that its bond is relatively weak.

Various proposals have been made heretofore whereby the packages or cartons enclosed within the rolled material may be fixedly retained therein, thus rendering the application of end closure means unnecessary. However, these proposals have not proven satisfactory or practical for one reason or another.

It is the principal object of the present invention, therefore, to provide a novel and improved type of device for confining and supporting packaged articles within a hollow roll, so as to dispense with the necessity of employing end closure or sealing means.

Other objects of the invention are to provide a device of the character indicated, which may

be readily inserted within the hollow roll and be retained therein against dislodgement during handling of the roll, yet capable of permitting convenient withdrawal of the packaged articles held thereby within the roll, without injuring the rolled material; to provide a device of this character designed so as to become securely lodged within the hollow roll by a wedging or frictional action of parts of the device on the surface of the core of the roll, and to provide a device designed and functioning as described, which will be efficient in operation and less costly than the presently used roll heads or caps.

Various other features and advantages of the invention will be more clearly apparent from the detailed description which is to follow and from the accompanying drawings, in which:

Fig. 1 shows a preformed blank of material for a device embodying the invention;

Fig. 2 is an elevational view partly in section showing the blank of Fig. 1 folded to its set-up form, in which it may be inserted in the roll;

Fig. 3 is an end view of Fig. 2;

Fig. 4 is a perspective view showing the manner in which the device is adapted to become wedged within the hollow opening of a cylindrical roll, parts thereof being broken away to clarify the showing;

Fig. 5 is a sectional view showing the manner in which one or more packaged articles may be confined and retained within the axial opening of a cylindrical roll by means of the device of Figs. 1 to 4;

Fig. 6 is a sectional view taken along lines 6—6 of Fig. 5;

Fig. 7 is a view similar to Fig. 1, showing another embodiment of the invention;

Fig. 8 is a side view, in elevation, showing the blank of Fig. 7 folded to operative position;

Fig. 9 is an end view of Fig. 8;

Fig. 10 is an enlarged perspective view, showing more clearly the details of construction of one end of the device shown in Fig. 8;

Fig. 11 is a sectional view similar to Fig. 5, showing the manner in which the packaged articles are held within a hollow roll of material by the device of Figs. 7 to 10; and

Fig. 12 is a sectional view taken along lines 12—12 of Fig. 11.

Referring to Fig. 1, the blank 14 comprises a unitary sheet of foldable material, such as corrugated boxboard or the like, from which the box-like receptacle or container 15 is formed. After cutting away portions along the peripheral edges, as shown, the blank is creased along two

parallel longitudinal lines and along four transverse lines that cross or meet the longitudinal lines substantially at right angles, thereby dividing it into pairs of flaps and extensions foldable relative to a central portion.

The central rectangular portion thus defined constitutes the bottom 16 of the receptacle or container 15. The panels contiguous with the longer edges of the bottom portion 16 constitute side walls or flaps 17 hinged along the substantially parallel fold lines 18. The panels contiguous with the narrow edges of the bottom portion form the main end flaps 19, which are adapted to bend upwardly toward each other when folded along the creases 20. These main end flaps 19 are creased along substantially parallel lines 21 and 22 to form, respectively, pairs of side extensions or flaps 23 and 24 adapted to fold upwardly toward each other. The end flaps 19 are also creased along transverse lines 25 and 26 to form, respectively, upwardly folding end extensions 27, 28. Each of the end extensions 27, 28 has a pair of substantially triangular wings 29 and 30 adapted to fold inwardly toward each other along substantially parallel creased lines 31 and 32.

In setting up the receptacle or container 15 from the thus described blank 14, the opposite pairs of end wings 29 and 30 may be folded inwardly toward each other and then the end extensions 27 and 28 may be bent upwardly along the fold lines 25, 26 until the end wings 29 and 30 respectively meet inwardly folded pairs of end flaps 23 and 24, as shown in Figs. 2 and 4. The main end flaps 19 are thus provided with upwardly extending walls on three sides as defined by the fold lines 21, 25 and 22, 26. In this formation, the main end flaps 19 are folded upwardly along the lines 20 until the edges 33, 34 come to rest along the bottom portion 16. The main end flaps 19 are retained in this box-like formation by folding the main side flaps 17 upwardly along the fold lines 18 to thus form a practically completely enclosed container, as shown in Figs. 2 and 3.

The height and width of the box-like receptacle or container 15 are proportioned according to the inner diameter of the central opening of the roll of material with which it is to be associated, so as to afford at least the minimum amount of clearance required to freely insert the receptacle within the hollow opening of the roll. The length of the container is somewhat in excess of the overall length of the packages to be held thereby in the central opening of the roll, so that the contained packages will not hamper or restrain the inward pivotal movement required of the main end flaps 19 in closing the container sufficiently to permit it to be readily inserted within the central opening in the roll.

In the use of the device, one of the flaps 19 and its extensions 23, 27, 29 may be folded to the set-up position and this closed end of the container then inserted into the axial opening 35 of the rolled material 36, whereupon a can of cement 37 and a package of nails 38 may then be placed within the container 15, after which the other end of the container is similarly folded to close that end, and the insertion of the container into the opening may then be completed. It is also within the contemplation of the invention to load the formed container with the packaged articles and then to insert the loaded container within the axial opening of the roll. To this end, suitably shaped jigs may be employed

for bending the container blank along the fold lines previously described, and also for retaining the loaded container in closed formation until it is inserted within the roll opening. After the loaded container has been inserted within the opening 35 of the roll 36, the folded flaps, extensions and wings of the container will tend to spring outwardly and unfold along the hinges of their respective fold-lines, as best illustrated in Fig. 4. This tendency to unfold is largely attributable to the normal resiliency of the corrugated boxboard from which the container is formed. The effect of this unfolding action is to cause opposite edges and corners of the container to frictionally contact the wall of the opening 35.

Whenever the roll 36 is set on one end, or even slightly inclined from a horizontal plane, as will generally happen under normal handling of the roll, the container 15 will normally tend to slide or shift somewhat toward the lower end of the roll. However, the friction or drag set up between the contacting portions of the container and the wall of the opening 35, will cause the upper end flaps 19 to pivot outwardly along the hinge of the fold-line 20, and the end extension 28 to pivot outwardly along the hinge 26. The outward pivotal movement thus initiated in the flap 19, in effect, increases the transverse dimension (perpendicular to the base) of the receptacle, thereby causing the corners of the flap to engage and wedge against the wall of the opening 35, as indicated in Fig. 6. Thus, the entire upper end of the container is effectively wedged in place and the container immediately becomes immobilized.

As shown in Fig. 5, wedging action of a similar type also takes place at the lower end of the container since the lower end flap 19 is caused to pivot outwardly relative to the container under the weight of the packages 37 and 38 bearing against the flap 19.

It will be readily appreciated that bumping or jarring of the roll during handling, especially when setting the roll on one end, only serves more securely to wedge the container within the opening in the roll, since the added momentum of the bumping or jarring increases the friction or drag at the top end of the container. Such added momentum may also be transmitted through the contained packages 37 and 38 to the lower end of the container, with the result that a tighter wedging action takes place. It is, therefore, manifest that the container is designed to support packaged articles within the hollow roll and effectively to resist dislodgement when the roll is bumped or jarred, stood on either end, or reversed, or otherwise roughly handled.

The material from which the receptacle or container 15 is formed has sufficient body strength and rigidity to withstand the type of stress and strain to which it will be subjected during the handling of a roll of material.

When it is desired to utilize the "trimmings" confined within the roll, the wedged container may be readily released and removed by the use of some common expedient, such as a pole or stick to force the container out through the central opening in the roll.

Referring now to Fig. 7, a narrow, elongated form of blank 44 is therein illustrated, comprising a flat sheet of solid fiberboard, having cutouts and longitudinal and transverse score lines to form appropriately sized central, side and end portions of a trough-shaped receptacle 45. This modified type of receptacle for supporting packaged articles, such as cans of cement and cartons

or bags of nails, is adapted to carry out the objects of the present invention when used with rolled material having small axial openings, as compared to the larger size openings for which the receptacle shown in Figs. 1 to 6 is best suited.

In setting up the trough-shaped receptacle 45, as shown in Figs. 8 to 10, the bottom is formed by the rectangular shaped central portion 46 of the blank 44, bounded by the narrow side members 47 and end members 49. The side members 47 are folded upwardly toward each other along substantially parallel longitudinal score lines 48 and the end members 49 are adapted to fold upwardly toward each other along the transverse score lines 50.

A spaced double wall construction of the end portions of the container, as shown in Fig. 8, is attained by bending the opposite pairs of side flaps 53 and 54 upwardly toward each other along their respective score lines 51 and 52, until they are substantially at right angles with respect to the main end members 49. Then the octagonally shaped end extensions 55 are folded inwardly along score lines 56 and the integral hinge portions 57 are likewise folded inwardly along lines 58 until the end extensions come to rest substantially against the edges of the side flaps 53 and 54. The opposite pairs of ears 60, 61 extending from the hinge portions 57 are bent upwardly to overlap the protruding edges of the end extensions 55. In this position, the pairs of ears 60, 61 project laterally of and slightly toward the bottom 46 of the receptacle 45, thus serving as wedging aids, as will be more fully explained hereinafter.

The cans or packages of cement 62 and nails 63 may be placed within the trough-like receptacle 45 either before the receptacle is inserted into the opening 65 of a roll of material 66 by the use of suitably designed jigs, as previously explained in connection with the setting up and loading of container 15, or these packages may be thus positioned within the receptacle after one end thereof has been inserted part way into the opening of the roll.

When the roll 66 is placed on end, as shown in Fig. 11, or handled in such manner as to cause a sliding or shifting movement of the receptacle 45, relative to the wall of the opening 65, the upper pivotally connected end flap 49 will function in a manner similar to that more fully detailed above in connection with Figs. 1 to 6, thus serving to wedge the receptacle 45 within the opening 65. Additional wedging action is afforded by the laterally extending ears 60, 61, and the projecting edges of the octagonal walls 55, as shown in Fig. 12. The lower end flap 49 similarly functions as a second wedging member when the weight of the packaged articles 62, 63 bearing against the inner wall 55 causes the flap to pivot outwardly and more securely engage the wall of the opening. The same wedging engagement of the receptacle within the roll, whereby to prevent its dislodgement when the roll is handled, may be likewise obtained by reversing the position of the roll, as will be readily appreciated.

The spaced double-wall construction for the ends of the receptacle shown in Figs. 7 to 12 provides adequate reinforcement against any striking force of the packaged articles that is likely to occur under the added momentum of severe bumping or jarring of the roll. Furthermore, the pivotable end walls may be moved outwardly to a limited extent only, as determined by the 75

slight amount of clearance available between the receptacle and the wall of the opening, thus preventing the receptacle from opening up to such an extent as to permit the confined articles to freely slide out or to be forced out by rough handling and bumping of the roll.

It is thus seen that the holding devices of my invention function in a manner effective to confine packaged articles within hollow rolls of convolute material and prevent the dislodgement of the articles during the handling of the roll. The objective is accomplished with greater efficiency and at lower cost than can be obtained when caps or heads are utilized for sealing the open ends of the roll. The careful handling usually required for rolls in which the cement and nails are loosely confined by sealing the ends is no longer necessary, when the present invention is utilized. Moreover, with the application of the present invention, rough handling of the rolls only serves to more securely lodge the packaged articles within the rolls.

I claim:

1. In combination with a hollow roll, a device 25 for supporting packaged articles within said hollow roll, comprising a unitary piece of foldable material forming a container having a bottom member, side and end members hinged thereto, the largest diameter across the end members being greater than the diameter of the interior of the roll, said end members being adapted, when inclined with respect to the bottom member, securely to wedge within said interior and to hold said container within said hollow roll when said 30 roll is placed on end.

2. In combination with rolled sheet material, a device for confining and supporting packaged articles within the axial opening of said rolled sheet material, comprising a single piece of material 40 cut and bent to form a container for insertion, with articles contained therein, within said axial opening, said container having a bottom member, and a pair of end members hinged thereto, said end members terminating in pivotally connected 45 portions inclined toward said bottom member, the largest dimension across the end members being greater than the diameter of the axial opening, one of said end members adapted to wedgily engage the wall of said axial opening responsive to a slight shifting or sliding movement of the container, the other of said end members adapted to wedgily engage the wall of said axial opening when actuated by the weight of the articles within said container upon said other end member.

3. In combination with rolled sheet material, a device for confining and supporting packaged articles within the axial opening of said rolled sheet material, comprising a container or receptacle formed from a single sheet of rigid foldable material, said container or receptacle having a bottom member and inclined ends pivotally connected to said bottom member, the largest dimension across the ends being greater than the diameter of the axial opening, said ends, when inclined to said bottom member, being readily insertable within said axial opening, said inclined ends serving as wedges for immobilizing said container immediately, responsive to a slight shifting or sliding movement of the container when said roll of material is placed on either of its ends.

4. In combination with a hollow roll, a device for supporting packaged articles within said hollow roll, comprising a unitary piece of foldable

material forming a container having a bottom member and an end member hinged thereto, the largest dimension across the end member being greater than the diameter of the interior of the roll, said end member being adapted, when inclined with respect to the bottom member, securely to wedge within said interior and to hold said container within said hollow roll when the latter is placed on end.

5. In combination with rolled sheet material, a device for confining and supporting packaged articles within the axial opening of said rolled sheet material, comprising a single piece of material cut and bent to form a container for insertion, with articles contained therein, within the axial opening, said container having a bottom member, and a pair of end members hinged thereto, the largest dimension across the end members being greater than the diameter of the axial opening, said end members being capable of being inclined with respect to said bottom member, and, when so inclined, one of said end members being adapted wedgingly to engage the wall of said axial opening responsive to a slight shifting or sliding movement of the container and the other opposite end member being adapted wedgingly to engage the wall of said axial opening when actuated by the weight of the articles within the container upon said other end member.

6. In a means of the class described, the com-

bination with a member having a longitudinal tubular opening, of a holder formed of rigid foldable material, said holder comprising a side member and end flap means at its opposite ends, said end flap means being generally inclined inwardly with respect to the side member and substantially in converging relation with respect to each other both of said end flap means extending substantially transversely of the longitudinal extent of the opening and expansible laterally with respect thereto, both of said end flap means being adapted, when expanded, wedgingly to engage the wall of the opening when either the side member or end flap means are moved longitudinally with respect to the walls of the opening.

7. In a means of the class described, the combination with a member having a longitudinal tubular opening, of a holder formed of rigid foldable material, said holder comprising a side member and an integral end flap means at one end thereof, that portion of the end flap means which is integral with the side member being normally inclined inwardly with respect to said side member, said end flap means extending substantially transversely of the longitudinal extent of the opening and being expanded laterally into wedging engagement with the walls forming said tubular opening.

ASGER EILERSGAARD.
